C. L. ROBERTS

TOBACCO STEMMING MACHINE

Filed June 11, 1925

Patented June 15, 1926.

1,589,323

UNITED STATES PATENT OFFICE.

CHARLES LEWIS ROBERTS, OF LOUISVILLE, KENTUCKY, ASSIGNOR TO THE AMERICAN TOBACCO COMPANY, OF NEW YORK, N. Y., A CORPORATION OF NEW JERSEY.

TOBACCO-STEMMING MACHINE.

Application filed June 11, 1925. Serial No. 36,298.

This invention is an improvement in tobacco stemming machines, and more particularly in machines for removing in a substantially unimpaired condition the tip portions of the leaf containing the smaller stem portions which are utilizable in the manufacture of tobacco products.

A relatively large area of the leaf at the tip end which contains only stem portions of small cross section, is not necessarily involved in the stemming operation, for in this portion of the leaf, there is no stem of a size that will unfit the leaf for use in recognized processes.

15 This area includes from $\frac{1}{3}$ to $\frac{1}{2}$ of the leaf, and a like amount of the central stem, and in the usual methods of stemming, it is subjected to more or less handling by machinery, and a consequent liability to in-

jury.

20 One of two methods is usually practiced in stemming tobacco. In one the lamina is turned from the stem by mechanism which operates longitudinally of the leaf, generally 25 from the butt toward the tip. In the operation the lamina is more or less mutilated, and a relatively large portion remains with the stem.

In the other, the tobacco leaves are subjected to a disintegrating action, which separates the lamina from the stem portions in a more or less fragmentary condition, and with a very large proportion of very fine particles, which are not readily utilizable 35 in the ordinary processes to which the tobacco is subjected especially those which include flavoring.

One of the primary objects of the present invention is the provision of a step in the 40 method of handling tobacco, in the practice of which a relatively large area of the leaf is emancipated from the handling required in the stemming of the leaf.

Another object is the provision of a machine for carrying out the improved method, 45 wherein mechanism is provided for removing the tip portions of the leaves, while in the hand, in a substantially unimpaired condition, and prior to the operations designed 50 to remove the woody stem portions.

Another object is the provision in such a machine, of means to firmly grasp hands of tobacco during the transportation thereof past the removing mechanism, irrespec-

tive of the manner in which the hands are laid.

To the accomplishment of the foregoing, and such other objects as may hereinafter appear, the invention consists in the method, and in the construction and novel combination of parts fully described hereinafter, illustrated in the accompanying drawings, and pointed out in the claims appended here-to, it being understood that various changes in the form, proportion, size and minor details of construction within the scope of the claims, may be resorted to without departing from the spirit of the invention.

Fig. 1 is a longitudinal vertical section of the improved machine.

Fig. 2 is a plan view.

Fig. 3 is a plan view of a bunch of hands, showing the method of arranging the same, during the operation.

In the present embodiment of the invention, a suitable table 1 is provided, having supporting legs 2 and a super-structure 3. Carrier belts 4 and 5 are provided for transporting the tobacco longitudinally of the table. These belts are arranged at each side of the center of the table, and spaced apart, and are so supported that the upper runs of the belts move over the table top. The belt 4 is supported by rollers 6, while the belt 5 is supported by similar rollers 7.

The rollers 6 and 7 at the front end of the table are mounted on a common shaft 8, supported by the table, with the rollers directly below an opening 9 in the table, the arrangement being such that the belts pass through the opening 9 as they leave the rollers. The rear roller 6 is journaled below an opening 10 intermediate the ends of the table, and the rear roller 7 is journaled below an opening 11 at the rear. Chutes 12 and 13 are arranged at the openings 10 and 11 respectively, the former being designed to receive the butts of the leaves, and the latter the tips of the leaves.

The table has an opening 14 between the belts 4 and 5, and between the openings 7 and 10, and cutting mechanism is arranged at the opening. The said mechanism includes a toothed cutter disk 15 secured to a shaft 16 journaled below the table, and an upper disk or plate 17, secured to a shaft 18, above the table and between the top thereof and the super-structure. The edges

of the disks 15 and 17 lap, as indicated at Fig. 1 and the common chord sub-tending thelapping segments is level with the upper faces of the belts 4 and 5. The shafts 16 and 5 18, are driven from a suitable prime mover, not shown, as are also the rollers 6 and 7, and the tobacco is supplied to the belts 4 and 5 by an operator, who stands at an extension 19 at the left end of the table. An 10 endless belt or apron 20 carries the tobacco to the operator, the belt being supported by rollers 21 one of which is shown, said rollers being driven by the prime mover before mentioned.

15 The tobacco is fed to the machine, and through the machine, in hands, indicated at 22, and the hands are not unbound to operate upon the individual leaves, but the cutting is done with the leaves in the hand. 20 The hands are held down upon the feed belts 4 and 5, by means of pairs of endless chains 23, each pair cooperating with one 25 of the belts 4 and 5. The chains are supported by sprocket wheels 24 at one end of the table, and by sprocket wheels 25 at the other end. The wheels 24 are secured to a shaft 26, and the wheels 25 to a shaft 27, either of which, preferably the shaft 26, is driven by the prime mover before mentioned.

30 Referring to Fig. 2, it will be noticed that the members of each pair cooperate with one of the belts 4—5, the lower runs of the pair normally resting on the belt 4 or 5 as 35 the case may be. The chains are heavy, and are of such length that a large amount of slack is provided in the lower run of each chain. The slack lower runs lie upon the hands of tobacco moving with the belts 4 and 5, and hold the hands firmly down upon 40 the said belts during the operation of cutting. The upper runs of each pair of belts are supported by the super-structure 3 before mentioned, the said super-structure 45 having channel guides 28 through which the upper runs move. The hands are not necessarily separated or spaced in any manner, when they are fed upon the belts 4—5. They may be bunched, several hands in a 50 bunch, but the heavy, flexible chains will hold them firmly in place, whether a single hand or several. It will be understood that the tip portion of the leaf which is adapted for use, and the stem portion of which is 55 not involved in the stemming operation, amounts to from $\frac{1}{3}$ to $\frac{1}{2}$ of the area of the leaf, and its length is measured from the tip of the leaf. While the leaves are not of the same length, they are generally arranged 60 in hands, each of which includes a number of leaves of somewhat near the same length. Hence a cut transversely of the hand a selected distance from the tip will remove all of that portion of each leaf in the hand, 65 which is not involved in the stemming op-

eration. Because of the different lengths of the hands, the hands are not butted, but are preferably laid upon the belts 4—5, with the hand tips in something near alinement, as indicated at Fig. 2.

70 Tobacco treated in the manner just described, is especially adapted for use in the method set forth in my co-pending applications, Ser. Nos. 36,297 and 36,299 of even date herewith. The severed leaf tips are in 75 condition for further processing as they stand, and the butt portions may be subjected to the action of a disintegrator, to thoroughly break up the stem portions and detach the leaf portions therefrom, after 80 the stem portions have been separated from the leaf portions, the larger fragments thereof may be added to the leaf tips, which are dipped to flavor in the usual manner. The smaller fragments may be showered 85 onto the dipped pieces as described in the last mentioned application.

90 In the operation of the machine, the hands, which are fed to the extension 19 of the table by the belt 20 are placed on the belts 4—5 by the operator with the tip ends of the hands in approximate alinement. The hands either singly or bunched, are firmly grasped by the slack runs of the heavy chains, and are held against displacement. As the hands are advanced, they 95 reach the cutters 15—17, which sever the hands into two portions, one of which the butt portion contains all of the stem portion which it is desirable to remove. Just beyond the cutters and in alinement therewith, a partition 29 extends longitudinally of the table top. This partition acts as a deflector and guide for the tip ends of the leaves, and the butt ends of the hands, deflecting and guiding the former through the opening 11 and the chute 13, while the hand butt ends are guided to the opening 10, and through the chute 12.

100 I claim:

110 1. A machine for transversely severing tobacco leaves into tip and butt portions, including a feeding mechanism for moving the hands in a direction transverse to their length, said mechanism comprising a plurality of 115 means arranged in spaced relation to firmly grip the hands near the opposite ends thereof, and mechanism between the said means for cutting the hands transversely.

120 2. A machine for transversely severing tobacco leaves into tip and butt portions, including a feeding mechanism for moving the leaves in a direction transverse to their length, said mechanism comprising a plurality of means arranged in spaced relation 125 to firmly grip the leaves near the opposite ends thereof, mechanism between the said means for cutting the leaves transversely, and a plurality of discharge chutes for the portions, one to receive the butts and the 130

other the tips, and spaced apart from each other, the feeding means arranged to deliver the portions to the appropriate chutes.

3. A machine for transversely severing tobacco leaves into tip and butt portions, including a feeding mechanism for moving the leaves in a direction transverse to their length, said mechanism comprising a plurality of means arranged in spaced relation to firmly grip the leaves near the opposite ends thereof, and mechanism between the said means for cutting the leaves transversely, the cutters comprising cooperating cutting disks, one of which is toothed.
4. A machine for transversely severing tobacco leaves in the hand into tip and butt portions, including a feeding mechanism for moving the hands in a direction transverse to their length, said mechanism comprising a plurality of means arranged in spaced relation to firmly grip the hands near the opposite ends thereof, and mechanism between the said means for cutting the hands transversely, each of the said gripping means including a lower endless belt and a pair of chains above the belt, the lower runs thereof normally resting upon the upper run of the belt.
5. A machine for transversely severing tobacco leaves in the hand into tip and butt portions, including a feeding mechanism for moving the hands in a direction transverse to their length, said mechanism comprising a plurality of means arranged in spaced relation to firmly grip the hands near the opposite ends thereof, and mechanism between the said means for cutting the hands transversely, each of the said gripping means including a lower endless belt and a pair of

chains above the belt, the lower runs thereof normally resting upon the upper run of the belt, each chain of a length to provide a relatively large amount of slack on the lower run.

6. A machine for transversely severing tobacco leaves in the hand into tip and butt portions, including a feeding mechanism for moving the hands in a direction transverse to their length, said mechanism comprising a plurality of means arranged in spaced relation to firmly grip the hands near the opposite ends thereof, mechanism between the said means for cutting the hands transversely, each of the said gripping means including a lower endless belt and a pair of chains above the belt, the lower runs thereof normally resting upon the upper run of the belt, each chain of a length to provide a relatively large amount of slack on the lower run, and means for supporting the upper runs of the chains.

7. A machine for transversely severing hands of tobacco leaves into butt and tip portions, including cutting mechanism, a plurality of feeding means cooperating to advance hands of tobacco past the cutting mechanism, a discharge chute for each of the portions into which the hands is severed, and spaced apart from each other, the feeding means arranged to deliver to the appropriate chute, and means beyond the cutting mechanism to separate the butt and tip portions.

Signed at Richmond in the county of Henrico and State of Virginia this eighth day of June A. D. 1925.
